UNITED STATES PATENT OFFICE.

HENRY WENNEBORG, OF SPRINGFIELD, ILLINOIS, ASSIGNOR OF ONE-HALF TO ENOS E. SPINDEL, OF SPRINGFIELD, ILLINOIS.

LOCK FOR VENDING MACHINES.

Application filed June 9, 1921. Serial No. 276,221.

To all whom it may concern:

Be it known that I, HENRY WENNEBORG, a citizen of the United States, residing at Springfield, in the county of Sangamon 5 and State of Illinois, have invented a new and useful Lock for Vending Machines or the like, of which the following is a specification.

The invention primarily relates to locks 10 for vending machines such as are used in what are known as self-service stores; but with slight modification is obviously applicable for other uses as will hereinafter appear.

15 The purposes of the invention are to provide a lock comprising a series of separately operable latches capable of permutation and to provide a key comprising a series of blades or leaves also capable of 20 permutation in accordance with the various permutations of the latches of the lock; to provide a lock having interchangeable latches pressed from sheet metal which may be quickly and easily assembled and may 25 be variously interchanged to form different combinations of the latches of the lock; and a key usable with the lock and having interchangeable blades pressed from sheet metal which may be quickly and easily as- 30 sembed and interchanged in harmony with the assembled latches of the lock, thus admitting of a large number of permutations of the locking devices; and to provide a lock and its key which shall be dependable 35 in use, which may be manufactured at relatively small cost and which shall be capable of a very large number of permutations thus adding to the desirability and safety of the lock.

40 I have shown in the drawings a preferred embodiment of the lock attached at the discharge or outlet end of the chute of a vending machine and will first describe so much of the mechanism of the vending machine 45 as may be necessary to illustrate practical application and use of the lock; and will then describe in detail the construction of the lock proper and its key. Fig. 1 is a fragmentary view of the chute of a vending machine showing some of the parts in section, also showing articles of merchandise in place in the chute and the box; and also showing, in elevation, parts of the lock.

50 In self-service stores the chutes are ar-

ranged in series or batteries each battery comprising a plurality of parallel inclined chutes; for the present purpose however, it is necessary to illustrate a part only of one chute since all the chutes in a battery 60 are usually alike.

Fig. 2 is a sectional view showing the same mechanism and also showing means for signaling that the stock in the chute with which the lock is connected is almost 65 exhausted and showing means for preventing the use of the key when the stock is exhausted and the chute is out of commission.

Fig. 3 is a section through the box on 70 the line 3—3 of Fig. 1.

Fig. 4 is a greatly enlarged longitudinal section through the lock and through the key taken on the line 4—4 of Fig. 1.

Fig. 5 is an enlarged isometric view of 75 the throat of the lock.

Fig. 6 is an enlarged isometric view of the detached and inverted key.

Fig. 7 is an enlarged transverse section through the key taken on the line 7—7 of 80 Fig. 6.

Fig. 8 is an enlarged sectional view of one of the screws used to connect the blades of the key.

Figs. 9, 10, 11, 12 and 13, illustrate a 85 modified construction of the lock and its key.

The same reference numerals designate the same parts in all the views.

Numeral 37 designates one of a series of 90 stationary studding or vertical posts which support a series of chutes and separate them from each other. The chutes 14 are preferably long wooden troughs of rectangular cross section and each trough or 95 chute is oscillative on a stationary pivot 15.

Adjacent to the lower end of each chute is a stationary box 16 of rectangular cross section equipped with a cover 17, connected with the permanent structure by a hinge 25. 100

The cover is hinged on the main structure and is connected with the hinged chute for a purpose which will be explained later. For convenience in description, I have shown a can 18 in place in the chute and a can 19 in place in the box. The rod 20 extends transversely through the box and is connected with two arms 21 outside the box, one on each side. The upper ends of the arms 21 are connected by a rod 22 110

which traverses the longitudinal slot 23 in the cover 17. The parts being so connected that when the cover is raised as indicated in Fig. 1—the rod 20, being under 5 the article (in the present case the can 19), will raise the article so that it will be readily accessible to the user.

A bent lever 24 pivoted at the outer end of the door is used to raise the door and 10 is also used to push the key into the lock as will be described later.

A transverse bar 26 is fixed on the cover 17 (Fig. 2). Two lifting bars 27, one on each side of the chute 14, are connected with 15 the bar 26 by pivots 28 and are connected with the sides of the chute by pivots 29 so arranged that when the cover is raised the bars 27 will act to depress the free end of the chute. When the cover is raised the free 20 end of the chute being depressed, the can 18 contained in the chute will strike against the inner end of the bottom of the box 16 and will be thereby prevented from entering the box and cannot be removed from the 25 chute. When the cover is completely closed and locked the bottom of the chute will be in the same plane with the bottom of the box to permit a can from the chute to slide into the box each time that the cover is closed, 30 so long as any cans remain in the chute; but if, by accident or design the cover has been left unlocked and slightly raised, a can from the chute cannot slide into the box neither can it be removed from the chute 35 until the cover is closed and locked and the key is inserted to unlock the cover and the cover is again unlocked and raised to give access to the can which will then be in the box.

40 A bar 30 is fixed on and extends across the chute. An insulated bracket 31 is stationary on the inner face of the bar 30. An insulated blade 32 is also stationary on the bar. A lever 33 is pivoted at the free end 45 of the bracket 31 and has a weight 36. An electric generator 34 of any suitable or approved construction may be placed in any convenient relation to the tier of chutes. Adjacent to each chute will be placed an 50 electric bell 35 energized by the generator. While any can 18 remains in the chute, the member 36 will lie on the can and prevent the lever from gravitating to close the gap between the lever 33 and the blade 32; but 55 if a can be absent, the member 36 will gravitate downward with the result that the lever 33 will contact with the blade 32 and close the electric circuit to cause the bell 35 to ring and apprise the attendant that the 60 particular chute is empty and needs replenishing.

The locking mechanism, as a whole, comprises a lock-element A attached to the inner front wall of the box 16; a shackle element B attached to the cover 17 and adapted

to co-act with the element A; a permutable throat element C stationary in the lock casing and extended outwardly through the shackle element, and a permutable key D adapted to slide in the throat element. 70

The element A comprises a metal casing 40 secured on the inner front wall of the inclined box 16 and containing two series of approximately U-shape blades 41, one series being on each side of the central longitudinal line 42—42 of the casing. Short parallel longitudinal walls 43 inside the casing form in conjunction with the top and the bottom plates of the casing, a way 44 in which the key D slides freely. The lower end of the way 44 is in line with a stationary inclined key chute 45 through which successive used keys slide into a suitable receptacle 46 inside the compartment containing the merchandise chutes 14. Screw rods 47, 80 extend across the casing and support the blades 41 which are oscillative on the rods. Springs 48 secured in the lower ends of the respective blades 41 bear against rods 49 which extend through the casing. When 90 the key acts to press the respective blades outwardly, as will hereinafter appear, the springs 48 will be stressed and when the key has slid into the way 44 the springs will act to return the blades to their original 95 position.

Each blade 41 has a relatively short prong 50 and a longer prong 51. Each prong 50 has at its free end an inclined inwardly extended member 52. Each prong 51 has at 100 its free end an inwardly extended hook member 53. The blades 41 are interchangeable and may be of different thicknesses. Each blade is operative independently of any other blade. 105

The shackle structure B comprises two parallel L-shape plates 54 secured on the cover 17 and extending inwardly through the cover and through the opening 55 into the casing 40 in line with the way 44. 110

Each plate 54 has at its free end a wedge-shape shoulder-member 56 extending the full width of the plate.

The throat element C is a box like structure comprising a bottom plate 57, a top plate 58, and intermediate plates 59. Each plate has a series of holes to accommodate tubular bolts 61. The bolts 61 are internally screw-threaded and screws 62 screw into the bolts to firmly unite the parts. A 115 longitudinal rib 63 on the plate 57 guides the key D in line with the throat. The plates 59 are interchangeable and may be of different thicknesses and different widths. 120

A simple embodiment of the key D comprises a bottom plate 64, a top plate 65, and an intermediate plate 66; it is obvious however, that the assembled key may comprise a plurality of leaves which may be interchanged in harmony with the assembled 125 130

latches of the lock, thus admitting of a large number of permutations of the locking devices. The plates are united by bolts 69, similar to but shorter than the bolts 61 already described. Each of the plates 64, 65 and 66 has at each edge of one end of the plate a laterally extended and forwardly inclined member 70 adapted to engage on the members 52 of the respective blades 41 which are in the same plane with the plates, to press the free ends of the blades outwardly to cause the hook members 53 to withdraw from the shoulders 56, and when all the hooks have been withdrawn the shackle B and the cover 17 may then be raised by pulling upwardly on the lower member of the lever 24. The effect of raising the lower end of the lever will be to cause its upper member 24^a to push the key D inward, to cause the members 70 to pass the members 52 to permit the key to pass through the way 44 and slide downward to the finger 77, where it will remain until the can 19 has been removed. Continued upward pull on the lever will result in raising the cover to permit the user to remove the can. After the can 19 has been removed, the key D will slide downwardly through the chute 45 into the receptacle 46.

From the foregoing description it is obvious that when the key passes completely into the throat it cannot be withdrawn, but must slide inward and drop into the receptacle 46.

The above mentioned vending machines are primarily designed for use in self-service stores. Pursuant to the plan of use the customer or user will go into the store in which complete price lists will be conspicuously posted and will make a list of the articles he wishes to buy and will pay the check clerk for them and the clerk will issue to the buyer the number of keys necessary to give the buyer access to the articles and make sure that he gets all that he is entitled to, but not more. It is therefore necessary to provide means to prevent taking out more than one article each time the cover 17 is raised; and to provide means for showing conclusively that the key was inserted but no article was in the box 16 and therefore the buyer would be entitled to receive the listed value of the missing article.

I have already described means for signifying that the chute 14 is empty and will now describe the means to prevent complete travel of the key D through the throat C while the box 16 is empty; so that the presence of the key in the throat will confirm the buyer's claim that he could not use the key and is therefore entitled to receive the value of the missing article.

Brackets 71 (Fig. 2) are fixed on the casing 40. A lever 72 pivoted on the brackets 65 has an extension 73 at right angles to the

body of the lever and a finger 75 also at right angles to the body of the lever. A weight 74 fixed on the short member of the lever tends to gravitate downward to cause the finger 75 to enter the slot 46 in the adjacent plate of the lock casing. When there is a can 19 in the box the can will press against the end of the extension 73 to keep the lever 72 in the position shown, but if the can be absent the weighted member of the lever 75 will gravitate downward to cause the finger 75 to extend through the slot and across the way 44 under the key, to prevent further inward movement of the key, and the key being then wholly within the throat could not be extracted by any instrument ordinarily available.

To make sure that a can is taken out of the box each time that the cover is completely open the lever 72 is provided with a finger 77 which projects through a suitable slot 78 into the way 44 and prevents downward passage of the key through the way so long as the can 19 is in contact with the extension 73, but immediately upon removal of the can the weight 44 will gravitate downward to operate the lever to withdraw the finger 77 from the way 44, to permit the key to slide downward into the box and at the same time will cause the finger 75 to obstruct the way 44 adjacent to the lower end of the throat to prevent any other key from traversing the way before another can has arrived in the box.

If a user claims that he inserted a key but did not receive a can his key will be in the throat if the can is absent, or will be in the way 44 if the can which he should have taken is still in the box.

To guard against the use of counterfeit keys, or the wrongful use of genuine keys, the plates 41 of the casing are capable of variable arrangement relative to each other; the blades 59 of the throat are capable of variable arrangement relative to each other; and the leaves 64-67 of the key are capable of variable arrangement relative to each other. If it is discovered that a genuine key has been retained by a buyer and is being frequently used; or if it is found that a counterfeit key is being used; it will only be necessary to re-arrange the blades 59 of the throat and correspondingly re-arrange the plates 41 in the casing, to effectually prevent wrongful use of a genuine key and to prevent further use of the counterfeit key.

Modified construction.

I will now describe the modified lock and the modified key shown in Figs. 9, 10, 11, 12 and 13.

The box shape metal casing 80 is closed at one end, except an opening 81 to receive the hinge member of the shackle and an opening 82 to receive the hook-member of

the shackle; the other end of the casing is open.

The shackle 83 turns on a pivot 84 and has at its free end a notch 85 in which the 5 hooks 86 of the plates or leaves 87 engage.

A drawer 88 is adapted to slide into the casing through the open end of the casing. Stationary stops 89 and 90 limit inward sliding of the drawer. The stop 90 has an inwardly extended member 91, having a hole 92 in line with the opening 82 and adapted to receive a screw 93 introduced through the opening.

An L-shape keeper 94 is slidable upwardly 15 in the casing to cause its member 97 to engage the stop 89. A screw 95 connects the keeper with the casing. The keeper has an internally screw-threaded bore 96. In the bottom of the drawer 88 is a hole 98 in line 20 with the bore 96, the hole 92 and the opening 82. When the parts are assembled as shown in Fig. 9, the screw 93 will unite the drawer and the keeper to the casing so that they cannot be disconnected while the lock is 25 locked.

A series of interchangeable plates 87, each having a hook 86, are oscillative on a removable screw 99 transverse to the drawer 88. Springs 100 supported on a rod 101 30 transverse to the drawer, act on the respective plates 87 to normally hold the hooks in the notch 85 of the shackle.

The key comprises a handle 102, a shank 103 having a transverse mortise 104, a series 35 of interchangeable leaves 105 situated in the mortise 104 and a screw 106 screwing into the end of the shank and firmly holding the leaves in the mortise.

A key hole 107, in the wall of the casing, 40 accommodates the key in such relation to the plates 87 that upon rotating the key the leaves 105 will move the respective blades 87 simultaneously to withdraw all the hook members 86 from the notch 85, to release the shackle so that its free end may be pulled 45 outwardly through the opening 82.

To assemble the lock the drawer 88 containing the plates 87 and the springs 100 will be pushed inwardly until the drawer 50 strikes the stops 89 and 90; the keeper will be slid inwardly until it strikes the stop 89; the screw 95 will be used to connect the keeper with the casing; and the screw 93 inserted through the opening 82, will be used 55 to connect the drawer and the keeper with the stop 90. To disunite the parts the procedure just described will be reversed.

If it be desired to change the position of the plates 87 relative to each other, the 60 drawer 88 will be slid out of the casing and the screw 99 will be withdrawn; the plates will then be arranged and replaced in the drawer; and the drawer will be replaced and secured in the casing.

65 To readjust the leaves of the key the screw

106 will be retracted and the leaves 105 will be taken out of the mortise 104 and will be re-arranged in the mortise and the screw will be tightened to hold them in place.

The operation of the modified lock is ob- 70 vious from the foregoing description.

Mode of use.

The user having paid for and received keys to the value of the articles which he 75 intends to buy will in succession go to the designated chutes containing the desired articles. He will note that the cover of the box at the end of each chute is closed so that the upper end of the throat is flush with the 80 top of the cover and will insert the proper key in the throat. He will then operate the lever 24 to push the key downwardly in the throat to unlock the cover, and to raise the cover, and will then take the article from 85 the box. If he wants another article from the same chute he will close the cover and insert another key to again unlock the cover and will again raise the cover and take out another article, and close the cover leaving 90 it locked in readiness for the next user; and so on for each chute visited.

Throughout the specification I have, for convenience in description, called the articles in the chute and box "cans"; but it is to be 95 understood that many other and different articles of merchandise may be used in the chutes and boxes of self-service stores employing the locking devices herein set forth.

I do not restrict my claims to the precise 100 details of construction shown and described, since minor modifications may be made within the scope of the claims and without departure from my invention.

Claims:

1. A lock comprising a casing, separately movable interchangeable blades in the casing, each blade having a wedge-member and a hook member; a shackle comprising two parallel members each having a shoulder 110 adapted to be engaged by the hook members of a plurality of blades; a laminated throat between said shackle members; and a key adapted to traverse said throat and having laterally extended members adapted to engage the respective wedge-members of said blades, to simultaneously withdraw the hook members of all said blades from both shoulder members of said shackle.

2. A key comprising a plurality of interchangeable leaves, each leaf having laterally extended inclined members, in combination with a throat of interchangeable plates arranged to permit free passage of the key; and oscillative blades in line with the throat 125 and simultaneously operative by the respective inclined members of the leaves of the key.

3. A key comprising a series of leaves each having a laterally extended inclined 130

- member, and one of said leaves having a longitudinal groove, and means detachably connecting said leaves; in combination with a throat having a longitudinal rib engaging 5 in said longitudinal groove of the key to guide inward movement of the key in the throat.
4. In a vending machine, the combination of an inclined chute adapted to permit down- 10 ward sliding of articles contained therein; a box in line with and receiving articles, one at a time, from said chute, a hinged cover closing said box; a key-actuated lock in said box and having a throat adapted to 15 receive a sliding key; a shackle attached to said cover and co-acting with said lock, and a gravitating intercepting-device normally retracted by the pressure of the article in the box and acting to intercept the key in the throat when there is no article in the box. 20
5. In a vending machine, the combination of a box; a hinged cover closing the box, a shackle attached to said cover; a lock in said box co-acting with said shackle and having a throat; a key slideable in said throat, and 25 a lever mounted on said cover and effective to push said key inwardly in said throat and also effective to raise said cover.
- In witness whereof I have hereunto signed my name at Springfield, Illinois, this 13th 30 day of May, 1921.
- HENRY WENNEBORG.
